UNITED STATES PATENT OFFICE.

GILBERTO PALAU, OF NEW YORK, N. Y.

DESIGN FOR A LADY'S HAND BAG.

Application filed May 24, 1928. Serial No 26,840. Term of patent 3½ years.

To all whom it may concern:

Be it known that I, GILBERTO PALAU, a citizen of the United States, and resident of the borough of Manhattan, city, county, and State of New York, have invented a new, original, and ornamental Design for Ladies' Hand Bags, of which the following is a specification.

Reference is to be had to the accompanying drawing, forming part hereof and which shows a face view of a lady's handbag embodying my new design.

I claim:

The ornamental design for a lady's hand bag, as shown.

GILBERTO PALAU.
